WATER HEATER

Walter W. Williams, Bloomington, Ill.

Application March 25, 1933, Serial No. 662,711

1 Claim. (Cl. 122—136)

This invention relates to water heaters and more particularly to the construction of a water heater in which the water is heated from the flame of a fluid fuel burner.

5 It is an object of this invention to provide a device of the character described for the heating of water, for domestic or other purposes, in which the flame and heat produced from the flame of a fluid fuel burner is delivered by an air blast 10 through a flue entirely surrounded by the water to be heated and in which the heated gases are conducted back and forth in the flue to contact the entire heating surface of the flue to transmit such heat to the surrounding water. It is another 15 object of this invention to provide a small compact heater of this character for domestic purposes of horizontal cylindrical form in which the heat from a fluid fuel burner is conducted through a flue passing horizontally through the heater contacted on all sides with the water contained therein.

With these and other objects in view, reference is made to the accompanying sheets of drawings illustrating a preferred form of this invention 25 with the understanding that minor detail changes may be made without departing from the scope thereof:

In the drawings;

30 Figure 1 is a view in end elevation of a preferred form of this heater.

Figure 2 is a fragmentary view in side elevation, with parts broken away and shown in section of Figure 1.

35 Figure 3 is a view in longitudinal central vertical section of this improved heater, with parts shown in side elevation.

Figure 4 is a detail view in section of the flue taken on the line 4—4 of Figure 3 looking in the direction of the arrows.

40 Figure 5 is an enlarged fragmentary detail view partly in section taken on the line 5—5 of Figure 3 looking in the direction of the arrows.

Figure 6 is an enlarged fragmentary detail view in end elevation of Figure 5.

45 Figure 7 is a view in transverse vertical section taken on the line 7—7 of Figure 3, looking in the direction of the arrows.

Figure 8 is a view in transverse vertical section taken on the line 8—8 of Figure 3, looking in the direction of the arrows.

50 Figure 9 is a view in transverse vertical section taken on the line 9—9 of Figure 3, looking in the direction of the arrows.

Figure 10 is a view partly in end elevation and partly in vertical section taken on the line 10—10 of Figure 3, looking in the direction of the arrows.

55 Figure 11 is a fragmentary enlarged view of one of the ignition electrodes, partly in central horizontal section with parts shown in top plan view.

60 Figure 12 is a transverse sectional view of

Figure 11, taken on the line 12—12, looking in the direction of the arrows.

Figure 13 is an enlarged detail view in front elevation of the heat control.

Figure 14 is a view in side elevation of Figure 13, 5 with the cover plate removed.

The embodiment of this invention as illustrated includes a horizontal cylindrical casing 1 which is closed at each end with a horizontal cylindrical flue 2 preferably mounted in the end closure plates 10 3 and 4 eccentrically to the horizontal axis of the casing 1 but out of contact therewith and extending beyond the said end closures at each end. The casing 1 is surrounded by an exterior spaced 15 apart casing 5 with similarly spaced apart ends 6 and 7 through which the flue 2 passes and the space between the inner and outer casing and inner and outer end closures is filled with a heat insulating medium such as asbestos wool. It is preferable to construct the inner and outer casings 20 1 and 5 with their respective end closures as well as the flue 2 of metal. It is preferable to support the heater in horizontal position upon spaced apart legs 8 at each end in supporting engagement with the exterior extending end portions of 25 the flue 2. Water is admitted to the interior of the heater through the inlet pipe 9, connected to any source of water supply, and the heated water which entirely surrounds the flue 2 is connected from the heater by the discharge pipe 10 to 30 its place of use.

The flue 2 supports a fluid fuel burner mechanism at one exterior end, the other exterior end being provided with a closure plate 11 having a reduced circular opening 12 and extension leading 35 from the bottom of the flue to conduct the gases of combustion therefrom to a smoke pipe or stack 13 leading to a chimney or outside atmosphere.

The end of the flue next to the fluid fuel burning mechanism is provided with a cylindrical lining 14 of refractory material, the lower portion of which terminates in a vertical end wall 15, and the upper portion of which is cut away thereabove, as shown in Figures 3, 4, and 7. The refractory sleeve 14 extends approximately one-third of the entire length of the flue 2. A refractory baffle is provided which includes an upper flat horizontal member 16 engaging and resting in a centrally notched portion of the end wall 15, extends to the opposite end closure 11 of the flue 45 50 and engages the side walls of the flue, as shown in Figures 4 and 8. This member 16 is also supported on two depending legs 17 and 18 resting upon the bottom of the flue and equally spaced from the vertical center plane thereof. Each of these supporting members 17 and 18 are similarly cut away at the end adjacent the wall 15, as indicated at 19 in Figure 3, and likewise the portion of the horizontal member 16 is cut away at the end adjacent the flue closure 11 from the exterior 55 60

sides of the legs to the flue wall, as indicated at 20 in Figures 4 and 9.

It is therefore seen that the cylindrical refractory lining 14, with a cut away end wall 15, provides a combustion chamber for the fluid fuel burner mechanism which communicates through the opening at its upper end to the passageway formed between the metal walls of the flue and the upper side of the horizontal refractory member 16 to conduct the gases of combustion in contact with the metal walls of the flue to the further end thereof whereupon the gases are divided and pass through the openings 20 to enter the spaced apart passageways between the supporting refractory members 17 and 18 and the metal casing of the flue until they impact upon the end wall 15 and are deflected through the openings 19 adjacent thereto and are united to pass through the central passageway between the refractory supports 17 and 18 and come in contact with the bottom of the flue casing and thereafter pass out through the opening 12 in the end closure of the flue to the stack 13. By the above construction it is seen that the gases of combustion of the fluid fuel burner are passed back and forth to continuously contact the entire circumference of the flue 2 after they leave the combustion chamber formed by the walls 14 and 15 thereby transmitting the maximum amount of heat from said gases to the surrounding water.

By the particular arrangement of the flue passages, the greatest heat from the flame is transmitted to the hottest portion of the water and is graduated downward toward the bottom of the heater where the cold water enters.

The fluid fuel burner mechanism supported upon the end of the flue 2 is preferably of the type illustrated in this applicant's prior Patent 1,831,277 of November 10, 1931, embodying the improvements illustrated in this applicant's pending application Serial No. 648,966, filed December 27, 1932, with certain changes to adapt this particular type of fluid fuel burning mechanism to this particular purpose. As shown in Figure 3, the fluid fuel burner mechanism is mounted within a casing 21 mounted on and supported by the exterior end of the flue 2. The casing 21 supports, preferably upon the upper side thereof, a housing 22 which supports and encloses an electric motor M with a blower fan 23 and a fluid fuel pump 24 upon the horizontal driving shaft 25 of the motor, whereby air is delivered under pressure through the housing into the chamber therebelow formed in the casing 21 and fluid fuel from the pipe 26 leading to a source of fluid fuel, not shown, passes through the fluid fuel valve in the casing 27 to the metering pump 24, and metered thereby into the pressure pump 29 which at the same time draws air through the air muffler 30 and delivers air and oil through the pipe 31 to deliver the fluid fuel under pressure at the nozzle 32 by way of the float chamber 33 in accordance with said applicant's prior Patent No. 1,831,277. An ignition device, in the form of electrodes 34 supported in the walls of the casing 21 and extending in advance of the nozzle 32 and connected to a transformer 34^a, is provided to ignite the fuel in the usual manner of devices of this type.

It is preferable to mount the electrodes 34 of the ignition device in the manner shown in Figures 11 and 12, in which each electrode 34 is connected to the wire 34^b leading to the transformer 34^a by means of a connecting bar 34^c

mounted axially within an insulating sleeve 34^d of porcelain or other non-conducting refractory material. The connecting bar 34^c is provided with its end adjacent the electrode 34 with a sleeve 34^e secured thereto which is received within a recess in the end of the insulator 34^d. The other end of the insulator is also recessed and the connecting bar 34^c projects therein and is screw-threaded, as shown. The terminal 34^f of the wire 34^b is inserted in this recess and held in place by the screw-threaded cap 34^g threaded on to the connecting bar and closing the opening in the insulator. The insulator is inserted through an opening in the casing 21 and is provided with an outstanding flange 34^h on the outer end adapted to engage the exterior of the casing wall. An annular split key 34ⁱ is inserted in oppositely disposed grooves 34^k in the walls of the insulator upon the interior of the casing and screws 34^l are threaded through opposite sides 27 of the key to engage the inner side of the casing wall to draw the flange 34^h against the exterior of the wall and hold the insulator rigidly in place.

The casing 21 is semi-spherical in shape and provides a somewhat spherical shaped chamber 35 for receiving the air delivered from the fan 23 at an angle to the axis of the flue 2. The nozzle 32 and ends of the electrodes 34 pass through an opening 36 in the vertical wall 37 in the casing 21 preferably but not necessarily concentric with the axis of the flue 2. A short cylindrical discharge or air pipe 38 with tapering walls is secured about the said concentric opening 36 and is provided with a plurality of angularly disposed deflector blades 39. The space between the walls around said opening 36 and the periphery of the chamber 31 is preferably filled with refractory material as indicated in Figure 5 and a peep opening 40 is provided therein, covered with isinglass or other transparent heat resisting material, for observing the presence or absence of the burner flame.

The air under pressure from the fan 23 enters the chamber 35 at one side of, or out of alignment with, the air pipe 38, expands within the chamber reducing its velocity pressure before passing through the air pipe 38 under only the static pressure of the fan which allows the fuel to burn with a short flame, insures the flame burning in the combustion chamber, and reduces the velocity of the travel of the gases of combustion through the passages in the flue.

In water heaters of the character described, it is not only preferable, but almost necessary, to provide an automatic control to regulate the temperature of the water and it is a further object of this invention to provide a heat control in connection with the heater disclosed.

This heat control includes a casing 41 preferably mounted upon the exterior of the end closure 6, as shown in Figures 1 and 3, which is connected by a tube 42 to a bulb 43 preferably positioned within the water above the flue 2, as shown in Figure 3. The other end of the tube 42 is connected to metallic bellows 44 mounted within the casing 41. The bulb, tube and bellows are filled with a gas or a liquid or both which readily responds to temperature changes, such as acetone, whereby an increase in temperature causes the liquid or gas to expand and thereby expand the bellows.

As shown in Figure 14, the top of the bellows is covered by a cap 45 having a centrally upstanding pin 46 in engagement with the underside of the pivoted lever 47. The opposite side of the

lever is engaged by a pin 48 depending from a flanged member 49 supporting the lower end of a heavy coil spring 50, the upper end of which is engaged by a circular plate 51 having diametrical-
 5 ly opposite apertures for sliding engagement with oppositely disposed pins 52 carried upon a gear wheel 53 whereby rotation of the gear 53 will impart rotation to the plate 51. The plate 51 is screw-threaded upon a central fixed threaded
 10 shaft 54. The gear upon the wheel 53 is a miter gear meshing with the corresponding miter gear 55 carried upon a rotating shaft 56 passing through the side of the casing 41 mounting upon the exterior thereof a hand wheel 57. Rotation
 15 of the hand wheel in one direction transmits a rotative motion to the plate 51 causing it to increase the tension upon the spring 50 which is transmitted to the upper side of the pivoted lever 47 while rotation in the opposite direction decreases the tension of the spring.

Whenever the expansion of the bellows overcomes the tension of the spring, an upward movement is imparted to the pivoted lever 47. A contact carrying arm 58 is pivoted at its lower end adjacent the free end of the pivoted lever 47 and mounts adjacent its upper free end a contact 59 normally held in engagement with a corresponding contact 60. Adjacent the free end of the lever 47 a projection 61 is provided which upon upward movement is adapted to engage a pin 62 so carried by the pivoted contact arm 58 that upon continued movement of the lever 47 the arm 58 will be rotated to open the contacts 59 and 60, as shown in dotted lines in Figure 14, and as soon as the bellows contracts, will allow the contacts 59 and 60 to again engage. The contact 60 is electrically connected to a wire 62^a which leads to binding post 63, Figure 13. The contact 59 is connected by a wire, not shown, to the binding post 64. These binding posts are connected by wires 65 and 66 to a junction box 67, as shown in Figure 1, and are therein connected in series with the electric circuit to the motor M.

As shown in Figure 13, the hand wheel 57 carries an indicator 67 and the casing thereabout is calibrated into divisions indicating degrees of temperature so that by rotating the hand wheel to bring the pointer to the degree desired, the tension upon the spring 50 will be so regulated that when the water within the boiler has been heated to that degree, the bellows will expand sufficiently to break the motor circuit and the fluid burner will cease operating and, conversely when the temperature of the water becomes lower than the desired degree, the bellows will contract and the motor circuit will be closed to cause the fluid fuel burner to operate and again apply heat.

The fluid fuel burner is preferably provided with the usual safety devices and controls and, as illustrated in Figures 3 and 10, a commercial stack safety device 68 is preferably mounted in the reduced extension 12 of the flue 2 having the customary thermal element 69 extending therein to be subjected to the flue gases in the same manner as in a domestic furnace. Inasmuch as the stack safety is not a part of this invention and is a part of commercial controls for fluid fuel burners, it is thought that it is only necessary to state that the normal function of a stack safety is to prevent the operation of a fluid fuel burner if combustion does not occur initially when the heat control calls for heat or in the event

of flame failure during the normal running operation.

The advantages of a heat control in a water heater of this type, in which the heat is supplied either intermittently or continuously, according to requirements, is obvious. If water is to be drawn from the heater intermittently then the supply of heat to the water should be intermittent to maintain a supply of water of a constant temperature, on the other hand, if the hot water is to be drawn off continuously then the supply of heat to the cold water entering the heater should be continuous. The hot water is drawn off at the top and the cold water enters the heater at the bottom, preferably under the flue and is progressively heated as it ascends about the flue. The bulb of the heat control is preferably located in the water above the flue. By setting the hand wheel of the heat control at the temperature desired of the water to be drawn off, the heat control will cause heat to be supplied to the water until that temperature is produced in the heater and then discontinue the heat supply. If the water is drawn off continuously and in sufficient volume to cause the incoming cold water to reduce the temperature surrounding the heat control bulb, it will act immediately to again supply heat, continuously if necessary, otherwise the heat control supplies heat to the incoming water intermittently. The heat control is actuated by the temperature of the heater water to operate the fluid fuel burner to supply heat to the water in the heater whenever its temperature drops below that set by the hand wheel of the heat control. In other words, the heat control is automatically controlled by the temperature of the water in the heater to automatically maintain the desired temperature in that water.

What I claim is:

In a water heater, the combination of a horizontal cylindrical water tank provided with means for admitting cold water at the bottom and removing heated water from the top thereof, with a horizontal flue passing through the water tank surrounded by the water to be heated, a lining about the interior of the flue of refractory material adjacent the fuel end adapted to form a combustion chamber for the fuel terminating in a vertical end wall cut away at the top, a closure for the opposite end of the flue having a reduced discharge opening therein, and a refractory deflecting baffle extending from the end of the combustion chamber to the opposite end closure of the flue, adapted to pass the heated gases of combustion back and forth and back again in contact with the flue walls and then through the reduced discharge opening whereby the gases are caused to progressively approach the coolest water contacting the flue as the temperature of said gases progressively decreases, said baffle including a horizontal portion extending from wall to wall of the flue and depending spaced apart parallel portions engaging the walls of the flue, said horizontal portion engaging the top of the end wall of the combustion chamber and extending to the opposite end closure being cut away adjacent thereto on the exterior of the depending portions and said depending parts being cut away adjacent said end wall with the passage formed between the depending portions connecting with the reduced discharge opening.
